CLAIM

The ornamental design for the display screen with graphical user interface, as shown and described.

DESCRIPTION

FIG. 1 is a front view of a first embodiment of a display screen or portion thereof with graphical user interface showing our new design;

FIG. 2 is a front view of another embodiment thereof;

FIG. 3 is a front view of another embodiment thereof;

FIG. 4 is a front view of another embodiment thereof;

FIG. 5 is a front view of another embodiment thereof;

FIG. 6 is a front view of another embodiment thereof;

FIG. 7 is a front view of another embodiment thereof;

FIG. 8 is a front view of another embodiment thereof; and,

FIG. 9 is a front view of another embodiment thereof.

The outermost dot-dash broken lines in the drawings illustrate a display screen or portion thereof that forms no part of the claimed design. The remaining dashed broken lines in the drawings illustrate portions of the graphical user interface that form no part of the claimed design.

1 Claim, 9 Drawing Sheets
